WRENCH

Rudolph Steinacher, New York, N. Y.

Application November 12, 1942, Serial No. 465,317

2 Claims. (CL. 81—165)

The general object of the present invention is to provide a sliding jaw wrench of improved construction. More specifically, the object of the invention is to provide a sliding jaw wrench of relatively simple and inexpensive construction and comprising threaded jaw adjusting provisions characterized by their capacity for easily and positively effecting rapid jaw adjustments.

The various features of novelty which characterize my invention are pointed out with particularity in the claims annexed to and forming a part of this specification. For a better understanding of the invention, however, its advantages, and specific objects attained with its use, reference should be had to the accompanying drawing and descriptive matter in which I have illustrated and described a preferred embodiment of the invention.

Of the drawing:

Fig. 1 is a side elevation of a wrench, partly in section on the line 1—1 of Fig. 2;

Fig. 2 is a section on the broken line of 2—2 of Fig. 1; and

Fig. 3 is a section on the line 3—3 of Fig. 1.

My improved wrench in the preferred form illustrated in the drawings, includes an elongated handle member or shaft A which terminates at one end in an enlarged head. The latter comprises a stationary jaw B and is formed with a transverse slot C into which the shank D of the movable jaw E of the wrench extends. Parallel grooves C' in the inner side walls of the slot C form a guide-way for the shank D which is formed at its opposite sides with ribs extending into and movable longitudinally of said grooves. The juxtaposed work engaging faces b and e of the stationary and movable wrench jaws B and E respectively, are shown as plane surfaces inclined to the longitudinal direction of the handle A at an angle which may be and as shown is a 30° angle. The guide-way grooves C' are perpendicular to said surfaces and are shown as rounded and the ribs of the shank D received in said grooves are similarly rounded and form the opposite sides of the wall of a spring chamber D' which extends into the shank D from the edge of the latter adjacent the jaw B.

A spring abutment pin F coaxial with the passage D' has one end extending into said passage and has its other end anchored in the slot C adjacent the edge of the latter remote from the jaw E. The jaw E is biased for movement away from the jaw b by a helical compression spring located in the passage D' and acting between the inserted end of the abutment pin F and a portion

of the shank D forming an abutment wall which closes the end of the passage D' remote from the stationary jaw B.

The edge D² of the shank D at the opposite side of the latter from the jaw E, is substantially perpendicular to the longitudinal direction of the handle, and is normally engaged by the parallel edge of a plate-like shank portion H' of a nut H, the body portion of which is received in a slot I formed in the wrench handle and extending longitudinally of the latter. The slot I is open at the head end of the wrench to the slot C which forms an abutment guide-way for the shank portion H' of an abutment nut H. The latter is adjustable longitudinally of said slot, and the effect of such adjustment is to vary the distance between the work engaging jaw surfaces b and e. The nut I is prevented from rotating about its axis by the engagement of the flat sides of its shank H' with the side walls of the slot C.

The longitudinal adjustment of the abutment nut H in the slot I is effected by the rotation of an abutment shaft or strut J mounted in the handle slot I and having a threaded end part J' extending into, and in threaded engagement with the adjusting nut H. In the preferred construction illustrated, the abutment strut J has at its end remote from the nut H, a threaded end part J² which extends into and is in threaded engagement with a second abutment nut K. The latter is shown as formed separately from the part A, and having its body portion received in the slot I and formed with bifurcations K' which straddle the portion of the member A at the corresponding end of the slot I, and are secured thereto by a pin or rivet L.

The end parts J' and J² are oppositely threaded, so that they screw into the nuts H and K, respectively, when the abutment rod is rotated in one direction, and are retracted by a reverse rotation of the strut J. When the two parts J' and J² have the same thread pitch, the longitudinal adjustment of the nut H effected by a given rotative adjustment of the rod J, is twice as great as it would be if the latter were mounted in the wrench handle part A for rotative movement without longitudinal adjustment.

In the preferred construction shown, the body portion of the strut J is shaped externally to provide a coarse pitch thread in operative engagement with a nut N rigidly secured in a tubular member M surrounding the strut J. The member M is movable longitudinally of the slot I and is formed with opposite flat sides, parallel to

and cooperating with side edges of the slot I to prevent rotative movement of the member M and nut N as they are moved longitudinally of the slot.

The pitch of the threaded connection between each of the nuts H and K and the corresponding end of the adjusting strut J should be fine enough to be self-locking, so that reaction forces between the wrench and the work tending to spread the jaws B and E apart will not give rotative movement to the strut J. The threaded connection between the member J and nut N, however, has a thread pitch coarse enough to permit the member J to be readily rotated by movement of the nut N longitudinally of the slot I.

With the guide-way for the shank D of the movable jaw D inclined to the longitudinal direction of the handle as described, the axial adjustment of the nut H in one direction will cam the removable jaw F toward the stationary jaw B, and the movement of the nut in the opposite direction will permit the jaw E to move away from the jaw B under the action of the spring G.

With properly formed wrench parts shaped and arranged as described, wrench adjustments can be effected readily and rapidly and without requiring the application of lubricating oil to any portion of the wrench. In consequence of the operation without lubrication, and the manner in which the spring G is enclosed and the small exposure of threads by which the strut J is connected to the abutment nuts H and K, there is little opportunity for dirt to interfere with the operation of the wrench.

As will be apparent to those skilled in the art, the wrench structure illustrated is desirably simple and is capable of production at a relatively low cost. The wrench handle part A with its attached stationary jaw B and the movable jaw E with its shank D may each be die formed of suitable material, such, for example, as a nickel steel alloy containing about 5% of nickel, and the work engaging portions of the jaws B and E may be hardened or tempered by a suitable and relatively inexpensive heat treatment.

The strut member J may well be formed with a body portion which is initially square in cross-section and is threaded by a twisting action in which one end of the strut is rotated about the strut axis relative to the other end of the strut. The end portions J' and J² of the rod J may well have their threads formed by a thread rolling action of known type. The nut members H and K may also be externally shaped by die press action.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

Having now described my invention what I claim as new, and desire to secure by Letters Patent is:

1. In a sliding jaw wrench, the combination of a handle member having at one end an enlarged head portion which includes a jaw and is transversely slotted to provide jaw and abut-

ment guideways respectively inclined and parallel to the longitudinal direction of said member, a sliding jaw having a shank received in, and movable longitudinally of, said jaw guide-

way, a spring acting between said member and sliding jaw and tending to spread said jaws apart, a nut received and longitudinally movable in said abutment guideway and engaging said sliding jaw and holding the latter against movement away from said stationary jaw, a strut mounted in said handle member for rotation about an axis extending longitudinally of the handle member and having one end in threaded engagement with said nut and having its other end in oppositely threaded engagement with said member and means to rotate said strut whereby on its rotation it will simultaneously adjust itself relatively to said member and relative to said nut and by each of said relative adjustments cam said sliding jaw toward said stationary jaw or to permit it to move away from said stationary jaw under the action of said spring, depending on the direction of rotation of said strut.

2. In a sliding jaw wrench, the combination of a member comprising an elongated handle portion and an enlarged head portion at one end of said handle portion, said handle portion comprising a jaw and being slotted to provide a guideway inclined to the longitudinal direction of said handle portion and an extension of said inclined guideway in the form of a narrow slot having parallel side walls separated by a distance less than the distance between the correspond-

ing sides of said guideway, said member being also formed with an elongated slot in and extending longitudinally of said handle portion away from said head portion and intersecting said narrow slot and having its side walls trans-

verse to the first mentioned side walls and separated from one another by a distance substantially greater than the first mentioned distance, a sliding jaw having a shank comprising a portion fitting in and movable longitudinally of said guideway and a narrower portion extending into the said narrow slot and having its edge adjacent said handle portion at right angles to the longitudinal direction of the latter, a spring acting between said member and sliding jaw and

tending to spread said jaws apart, an abutment member mounted in and longitudinally movable in said elongated slot and reduced in thickness at one end to form a flattened shank portion which extends into said narrow slot and is of a width greater than the distance between the side walls of said narrow slot and has its end edge in abutting engagement with the first mentioned edge, said abutment being also formed with an internally threaded socket open at its opposite end, and a coarse pitch strut mounted in said elongated slot for rotation about an axis extending longitudinally of said handle portion and in threaded engagement with said abutment member, and an actuating nut in threaded engagement with said coarse pitch threads and slidable longitudinally with respect to said handle portion, and adapted on rotation of the strut to cam the movable jaw member toward said stationary jaw or to permit it to move away from

said stationary jaw under the action of said spring accordingly as said strut is rotated in one direction or the other.

RUDOLPH STEINACHER.
